IGNITION DISTRIBUTOR

Eugene C. Bettini, Birmingham, Mich., assignor to Holley Carburetor Company, Van Dyke, Mich., a corporation of Michigan

Filed July 1, 1960, Ser. No. 40,446

3 Claims. (Cl. 73—509)

The present invention relates to an ignition distributor and represents an improvement over the ignition distributor shown in Johnson Patent 2,905,162. Basically, the distributor is responsive to engine speed and an engine vacuum such for example as manifold vacuum, to effect a timing adjustment of the distributor.

It is an object of the present invention to provide in 15 mechanism of the character described a rotary construction including a centrifugal weight movable radially of an axis of rotation against spring means to a position determined by its speed of rotation, said centrifugal weight serving as a mounting for an expansible chamber responsive to an engine vacuum condition, the chamber including a movable wall mechanically connected to means for effecting a timing adjustment of the distributor including special sealing means.

It is a further object of the present invention to provide mechanism of the character described provided with means for effectively preventing leakage so as to render the device at all times fully responsive to variations in engine vacuum conditions.

More specifically, it is an object of the present invention to provide a centrifugal member slidable on a radially extending transfer shaft including an expansible chamber having a movable wall, means connected to the movable wall for effecting adjustment of the ignition distributor, and a pair of diaphragms connected to said transfer shaft, one of said diaphragms being connected to said centrifugal member, the other of said diaphragms being connected to said means.

It is a further object of the present invention to provide in a construction as described in the preceding paragraph, a main pressure responsive chamber slidable on a shaft, and a pair of balancing sealed chambers connected to said main chamber by clearance.

Other objects and features of the invention will become apparent as the description proceeds, especially when taken in conjunction with the accompanying drawings, illustrating a preferred embodiment of the invention, wherein:

FIGURE 1 is a plan view of the ignition distributor.

FIGURE 2 is a sectional view on the line 2—2, FIGURE 1.

FIGURE 3 is a greatly enlarged fragmentary sectional view also taken on the line 2—2, FIGURE 1.

The distributor which may be of the conventional design disclosed in Johnson 2,905,162, includes a rotary shaft 10 on the upper end of which is rotatably mounted a cam 12. The cam 12 is rotated at shaft speed but the mechanism disclosed herein effects angular adjustment of the cam relative to the shaft to control spark advance. Specifically, the angular position of the cam 12 relative to the shaft 10 is controlled by shaft speed and by a vacuum condition variable in accordance with engine operation such for example as manifold vacuum.

In order to accomplish the foregoing there is provided a housing 14 enlarged to include a chamber 16 which receives centrifugal and pressure responsive mechanism as will subsequently be described.

Intersecting the shaft 10 in the chamber 16 is a transfer shaft 18. The shaft 10 has an axially extending passage 20 including one or more radial passages 22 adapted to connect the axial passage 20 with an annular chamber 24 connected by a passage 26 to a fitting 28 to which is

2

connected a conduit leading to the engine intake manifold.

The transfer shaft 18 includes an elongated axially extending passage 30 and a short radial passage 32 which communicates with the axially extending passage 20 of the shaft 10. Movable devices 34 are slidably mounted on the transfer shaft 18 and include laterally extending arms 36 including forwardly extending portions 38 provided with pins 40 received in elongated slots at the ends of cam adjusting arms 42. It will be apparent that if the devices 34 as seen in FIGURE 1, move away from each other from the illustrated position, the cam adjusting arm device 42 will rotate in a clockwise direction.

Referring now to FIGURE 3, there is illustrated the mechanism which effects movement of the devices 34.

The radially extending transfer shaft 18 is provided at its outer ends with radially extending flanges 44 and a reduced pilot portion 46 which is received in a cylindrical seat 48 provided at the inner end of a guide shaft 50. The shaft 50 includes at its inner end a radially extending flange 52 which is connected to the flange 44 by suitable fastening means such as the rivets 54. The flanges 44 and 52 receive between them the inner edge of an annular flexible diaphragm 56.

The movable devices 34 each comprise a housing portion 58 to which the laterally extending arm 36 is connected, and a housing portion 60. The housing portion 60 has a peripheral flange 62 bent over a peripheral flange 64 to clampingly engage the outer edge of the annular flexible diaphragm 56. The housing portion 58 is provided with an atmosphere port 66 and the construction just described defines a sealed expansible vacuum chamber 68.

Also slideable on the guide shaft 50 is a centrifugal weight 70 including a recess 72 closed by a flexible diaphragm 74. The outer edge of the annular flexible diaphragm 74 is clamped to the centrifugal weight by an annular cover 76 and the inner end of the flexible diaphragm 74 is clamped between plates 78 carried by the housing portion 60 of the movable device 34. A compression spring 79 engages one of the plates 78 and urges the movable device 34 to the left as seen in FIGURE 3, relative to the centrifugal weight 70. The cover 76 includes an enlarged annular opening 80 which connects the space 82 to atmosphere. The diaphragm 74 defines with the recess 72 a sealed vacuum chamber 83. The guide shaft 50 is provided with an elongated axially extending passage 84 connecting with the passage 30 and provided with a radially extending passage 86 which extends to the interior of the chamber defined by the recess 72.

At its outer end the guide shaft 50 is provided with an element 88 including a plug portion 90 which closes and seals the outer end of the passage 84. The element 88 includes a radially extending flange 92 which cooperates with a radially extending flange 94 at the outer end of the guide shaft 50 to clampingly engage the inner edge of an annular flexible diaphragm 96. The outer edge of the flexible diaphragm 96 is clamped by a bent over flange portion 98 on the centrifugal weight 70 so as to define a sealed chamber 100.

The element 88 includes a threaded end portion 102 carrying a nut 104 which supports a spring seat 106. Extending between the spring seat 106 and shoulders 108 and 110 on the centrifugal weight are coil compression springs 112 and 114 respectively.

In operation the position of the centrifugal weight 70 is determined by the speed of rotation of the shaft 10, the centrifugal force at any particular speed of course being balanced by the forces of the springs 112 and 114. The application of manifold vacuum to the chamber 83 tends to draw the movable device 34 to the right as seen

in FIGURE 3, to a position determined by the compression of the spring 79.

In order for the centrifugal weight 70 and the movable device 34 to move instantly to the proper position on the guide shaft 50 and the transfer shaft 18, it is necessary to provide a free sliding fit for the movable elements. This in turn necessarily results in leakage between the chamber 83 and atmosphere. In accordance with the present invention the sources of possible leakage are caused to lead into independent and opposed sealed vacuum chambers so that the full manifold vacuum is always available to effect adjustment of the movable device 34 relative to the centrifugal weight 70. With this construction a very free sliding fit for the centrifugal weight and centrifugal device on the guide shaft 50 may be permitted, and in fact, if desired, the parts may be deliberately shaped so as to provide for communication between the chambers 83, 68 and 100.

It is of course apparent that air flow along the guide shaft 50 from the chamber 83 to the chamber 100 will result in evacuation of the chamber 100 to a sub-atmospheric pressure existing instantaneously within the chamber 83. Similarly, leakage flow of air along the guide shaft 50 from the chamber 83 into the sealed chamber 68 will result in sub-atmospheric pressure within the chamber 68 equal to that existing in the chamber 83.

It will be observed that the flexible diaphragms 56 and 94 have the same effective area so that the existence of identical sub-atmospheric pressures in these chambers produces a balance so that the position of the centrifugal weight 70 is determined solely by speed of rotation of the shaft 10. The diaphragm 74 is of larger effective area than the diaphragm 56 so that the position of the movable device 34 is determined by the difference between these areas.

The drawings and the foregoing specification constitute a description of the improved ignition distributor in such full, clear, concise and exact terms as to enable any person skilled in the art to practice the invention, the scope of which is indicated by the appended claims.

What I claim as my invention is:

1. In an engine ignition distributor, a drive shaft adapted to be driven at a speed proportional to engine speed, a cross shaft connected to said drive shaft and extending radially from opposite sides thereof, annular centrifugal weights freely slideable in guided relation longitudinally on the extending portions of said cross shaft at opposite sides of said drive shaft, spring means connected between said cross shaft and each of said weights opposing radially outward movement of said weights, annular recesses at corresponding sides of said weights surrounding said cross shaft, annular adjusting members on the extending portions of said cross shaft and freely slideable in guided relation thereon relative to said weights, annular flexible actuating diaphragms connected at their outer edges to the outer edges of said annular recesses and connected at their inner edges to said adjusting members, said diaphragms and adjusting members closing said annular recesses and defining therewith annular chambers surrounding said cross shaft which are sealed except for substantial fluid flow passages provided by the free sliding fit between said cross shaft portions, said weights and said adjusting members, coil compression springs in said annular chambers urging said diaphragms outwardly thereof to bias said adjusting members radially of said cross shaft relative to said weights, passage means in shafts adapted to connect said chambers to a source of engine vacuum, and flexible annular sealing diaphragms at opposite sides of both of said actuating diaphragms connected between said cross shaft extensions and said weights and adjusting members.

2. In an engine ignition distributor, a drive shaft adapted to be driven at a speed proportional to engine speed, a cross shaft connected to said drive shaft and extending radially from opposite sides thereof, annular centrifugal weights freely slideable in guided relation longitudinally on the extending portions of said cross shaft at opposite sides of said drive shaft, spring means connected between said cross shaft and each of said weights opposing radially outward movement of said weights, annular recesses at the radially inner sides of said weights surrounding said cross shaft, annular adjusting members on the extending portions of said cross shaft at the inner sides of said weights and freely slideable in guided relation thereon relative to said weights, annular flexible actuating diaphragms connected at their outer edges to the outer edges of said annular recesses and connected at their inner edges to said adjusting members, said diaphragms and adjusting members closing said annular recesses and defining therewith annular chambers surrounding said cross shaft which are sealed except for substantial fluid flow passages provided by the free sliding fit between said cross shaft portions, said weights and said adjusting members, coil compression springs in said annular chambers urging said diaphragms outwardly thereof to bias said adjusting members radially inwardly relative to said weights, passage means in shafts adapted to connect said chambers to a source of engine vacuum, and flexible annular sealing diaphragms at opposite sides of both of said actuating diaphragms connected between said cross shaft extensions and said weights and adjusting members.

3. In an engine ignition distributor, a drive shaft adapted to be driven at a speed proportional to engine speed, a cross shaft connected to said drive shaft and extending radially from opposite sides thereof, annular centrifugal weights freely slideable in guided relation longitudinally on the extending portions of said cross shaft at opposite sides of said drive shaft, spring means connected between said cross shaft and each of said weights opposing radially outward movement of said weights, annular recesses at corresponding sides of said weights surrounding said cross shaft, annular adjusting members on the extending portions of said cross shaft and freely slideable in guided relation thereon relative to said weights, annular flexible actuating diaphragms connected at their outer edges to the outer edges of said annular recesses and connected at their inner edges to said adjusting members, said diaphragms and adjusting members closing said annular recesses and defining therewith annular chambers surrounding said cross shaft which are sealed except for substantial fluid flow passages provided by the free sliding fit between said cross shaft portions, said weights and said adjusting members, coil compression springs in said annular chambers urging said diaphragms outwardly thereof to bias said adjusting members radially of said cross shaft relative to said weights, passage means in shafts adapted to connect said chambers to a source of engine vacuum, and flexible annular sealing diaphragms of equal area at opposite sides of both of said actuating diaphragms connected between said cross shaft extensions and said weights and adjusting members.
